(57) **CLAIM**

The ornamental design for a paper punch, as shown and described.

DESCRIPTION

FIG. 1 is a front perspective view of a paper punch showing the new design;

FIG. 2 is a front perspective view thereof;

FIG. 3 is a front view thereof;

FIG. 4 is a rear view thereof;

FIG. 5 is a right side thereof;

FIG. 6 is a left side thereof;

FIG. 7 is a top view thereof;

FIG. 8 is a bottom view thereof; and,

FIG. 9 is a front perspective view showing the storage compartment open.

The broken lines showing features and surfaces in the front view of FIG. 3 are included for the purpose of showing portions that form no part of the claimed design.

1 Claim, 9 Drawing Sheets

FIG. 1

FIG. 2

FIG. 3

FIG. 4

FIG. 6

FIG. 7

FIG. 8

FIG. 9
